UNITED STATES PATENT OFFICE

CHARLES TUTEUR, OF CHICAGO, ILLINOIS

DESIGN FOR A FLOWER STAND

Application filed March 10, 1930. Serial No. 34,813. Term of patent 7 years.

To all whom it may concern.

Be it known that I, CHARLES TUTEUR, a citizen of the United States, and resident of Chicago, in the county of Cook and State of Illinois, have invented a new, original, and ornamental Design for a Flower Stand, of which the following is a specification, reference being had to the accompanying drawing, forming a part thereof.

The figure in the drawings is a view in perspective of a flower stand showing my new design.

I claim:

The ornamental design for a flower stand substantially as shown.

Signed at Chicago, in the county of Cook and State of Illinois, this 16th day of February, A. D. 1930.

CHARLES TUTEUR.
